UNITED STATES PATENT OFFICE.

WILLIAM HERBERT FOWKES, OF CHICAGO, ILLINOIS, ASSIGNOR TO BUDA COMPANY,
A CORPORATION OF ILLINOIS.

LIFTING-JACK.

1,396,951.

Specification of Letters Patent. Patented Nov. 15, 1921.

Application filed March 8, 1919. Serial No. 281,388.

To all whom it may concern:

Be it known that I, WILLIAM HERBERT FOWKES, a citizen of the United States, and residing at Chicago, in the county of Cook and State of Illinois, have invented certain new and useful Improvements in Lifting-Jacks, of which the following is a specification.

My invention relates to those lifting jacks usually designated in the trade as ball-bearing screw-jacks, and has for its chief aim in general to improve the construction and increase the efficiency and utility of jacks of this type, and in particular to produce a quick-raising self-lowering jack, the self-lowering action of which is automatic.

One of the salient objects of the invention is to produce an automatic self-lowering jack capable of being ratcheted down should the jack stick when in load sustaining position; another object is the provision in a jack of a centrifugal frictional control constructed and arranged to automatically govern or uniformly retard the descent of the jack under differing load conditions by virtue of the variable centrifugal braking action set up in said control rendering it adaptive to whatever load is imposed upon it; a further object of my invention relates to the provision of driving mechanism comprising leverage increasing gearing arranged intermediate the operating stub shaft of the jack and such control, whereby the rotative speed of the moving parts of said control is materially increased over that of said shaft and to thereby obtain a corresponding leverage increment of braking power at said shaft; a further object of the invention is to intermediately provide said driving mechanism with a positive acting brake normally set to hold the jack against involuntary descent under load, said brake being manually releasable to instantly bring the centrifugal controlling device into action and thereby permit the jack to automatically descend under full control independently of said brake; and a further object of the invention is to so organize the automatic control and the coöperating gearing with its positive brake so that these parts together with the detachable casing that carries them constitute a self-contained mechanism, readily detachable without disturbance of the parts from the supporting sleeve of the jack and as readily attachable.

These, together with such other advantages as may be hereinafter described, or are incident to my invention, I attain by means of a construction illustrated in preferred form in the accompanying drawings, 60 wherein:

Figure 1 represents a vertical sectional view of a jack to which my invention is shown applied;

Fig. 2 is a view taken along the line 2—2 65 of Fig. 1 looking in the direction of the arrows, the lower part being in side elevation and the upper in partial cross-section;

Fig. 3 is a sectional view taken from the interior of the gear casing along the line 70 3—3 of Fig. 1; and

Fig. 4 is a fragmentary view of a slightly modified form of the control illustrated more particularly in Figs. 1 and 3.

Referring to the drawings, the reference 75 character 5 denotes the standard of the jack, and 6 designates the lifting sleeve movable thereon and having as parts thereof the head cap 7 and the gear plate or case 8. Within the upper end of the standard is mounted 80 the usual operating nut 9 carrying the lifting screw 10 which is preferably pitched for a quick action lift. Keyed to the upper reduced end of the screw 10 is a bevel gear 11 having a meshed engagement with a bevel 85 pinion 12 whose operating shaft 13 is journaled in an extended bearing 14 formed in the casing 8 and which is terminally provided with any suitable operating mechanism, the inner ratchet portion only of 90 which is indicated at 15. Within the head of the sleeve and between the opposed faces of the cap and bevel gear is a pair of superimposed bearing plates 16 and 17 provided intermediately with a series of anti-friction 95 members 18. The base of the jack is designated by the reference character 19.

Before passing to a specific description of the preferred component elements of the principal mechanisms involved in the invention, the following brief localization of these mechanisms may be of assistance in clarifying such description. The reference letter A indicates a ratchet mechanism about shaft 13 which idles during the lifting action of the jack, but is brought into operation upon any reverse rotation of said shaft. This reverse rotation under load is however normally prevented by the positive 100 brake B. Upon release of the brake the 110

centrifugal control C, or C' as modified in Fig. 4, comes into action to automatically govern the descent of the jack under its load, and thereby prevents any disability 5 occurring to the jack which would be the case were its descent not retarded.

These mechanisms are all associated and coöperative, and as a whole constitute a complete geared device devoid of any need 10 for manual adjustment to govern the self-lowering of the jack, the gearing being such as to multiply the leverage at mechanism C so that the increment of such leverage is applied through mechanisms B and A to shaft 15 13 in a simple but very effective manner.

Similar characters designate like parts of these mechanisms throughout the several figures of the drawings.

The ratchet mechanism A consists of a 20 ratchet 20 secured to the shaft 13 to rotate with it, and a loose spur gear 21 provided with spring pressed pawls 22 designed to ratchet idly over the teeth of the ratchet during the actuation of the shaft by the operating 25 mechanism to lift the jack, and to engage them to impart motion to said gear 21 upon reverse rotation of the shaft under the influence of a load unless positively checked by the brake B. The latter comprises a 30 large spur gear 23 marginally flanged at one side to form an annular friction band 24 and integrally provided on the other side with a small pinion 25 in mesh with the large spur gear 21, said gear 23 and pinion 25 being loosely mounted for rotation about a stub shaft 26 whose outer end 26' is threaded into an enlarged portion 8' of the casing 8. Within this band are a pair of cams 27 and 28, the former axially mounted 40 on a pin 29 threaded in the casing 8, and being provided with an arm 27' connected to the cam 28 at a point removed from its axis by a link member 30, which latter has a tension spring connection 31 with the cam 45 28 normally acting to maintain the camming faces in contact with the inner surface of the band at opposed points thereof. The cam 28 is secured to the inner end of a fulcrum shaft 32 which is journaled in 50 said enlargement 8' and is extended therethrough to rigidly carry at its outer end a lever 33 having a terminal finger piece 34 intermediate the guards 35 and 36 formed on the casing 8, the guard 36 also constituting 55 a finger piece when it is desired to manually depress the lever finger piece 34 toward it and thereby release the brake so that the automatic control C may function.

This control C contemplates the provision 60 of an annular friction band 37 secured to an inner wall portion 6' of the sleeve in any suitable manner concentric with the shaft 38, the latter having its outer end fixed in a hub portion 8'a of the gear case and loosely 65 carrying a sleeve 39 which is formed with a

pinion 40' in mesh with the large gear 23. The inner end of the sleeve is maintained against displacement by the hub 8'a and an enlarged portion 38' of the shaft 38, and is provided with a disk 40 which, as shown, is 70 rotatable in a vertical plane just within the open side of the band 37. Pivoted to opposed marginal portions of the inner face of the disk are weighted fiber brake shoes 41 the weighted portions of which are indicated at 42. These shoes may be held in position against the inner face of the band by the light helical springs 43 which extend between the lever arms 44 of the shoes and eyes 45 provided on a small disk 46 secured 80 to the sleeve. The tension of the spring is preferably of a quality permitting the ratcheting down of the jack by the shaft operating mechanism 15 should the jack stick under load, and to permit the leverage 85 increasing gearing to gain a prompt start upon release of the brake B. Instead of the springs 43, pins 43' may be advantageously employed to approximately position the shoes, as indicated in Fig. 4 which illustrates a modified form of weighted lever brake shoe embodying the short arm shoe 41', and the long lever arm 44' which is provided with the weight 42'. The pin 43' is so positioned that with the control at rest 90 a slight clearance normally exists between the shoe and the band.

Obviously, the disk 40 of the control is the high speed member of the mechanisms above described, and the centrifugal force 100 present during disk rotation tends to throw the weighted brake shoes outwardly against the brake band 37, to frictionally retard the descent of the jack sleeve, the frictional braking effect correspondingly increasing to 105 counteract any increase in the rate of disk rotation that might be set up due to heavy load conditions and thereby automatically check such increase of speed. Stated differently, the centrifugal braking action of the 110 control accommodates itself to variable loads which may be sustained by the jack and provides for a substantially normal rate of self-lowering descent within the capacity limit of the jack. Furthermore, it will be apparent that the leverage increase obtained through the gearing multiplies the braking effect of the control to gain an increment of braking power at the operating shaft 13, the lower speed member of the mechanisms. 115

From the foregoing, it will be seen that in the lifting action of the jack these stated mechanisms are at rest, the positive brake serving to prevent any involuntary descent of the jack, release of which brake by depressing finger piece 34 initiates the self-lowering movement of the jack. This movement, as already set forth, is then wholly governed by the automatic control, such control being characterized by an entire ab- 120

sence of manual adjustment or control whatever. The construction and arrangement of these mechanisms proper, and their relation to gear case 8, are along simple and efficient lines, and as a whole the device takes upon itself a very compact form inviting ease and economy in manufacture and the parts are readily assembled and applied to the jack. With the single exception of the band 37, all the parts may be brought together as a self-contained unit carried by the casing 8, uncoupling of which permits the removal of the unit. Other advantages will readily appear to those skilled in the art.

I do not desire to be understood as limiting myself to the precise details of construction, or to the exact arrangement of the various parts or elements as shown, as it is manifest that variations and modifications thereof may be made without departing in any way from the spirit and scope of my invention and improvements, the instant embodiment of which is illustrated in a preferred form. I therefore reserve the right to all such variations and modifications as properly fall within the scope of my invention and the terms of the following claims.

30 I claim:

1. In a self-lowering lifting jack, the combination of a stationary member, a lifting member movable thereon, a revolute actuating member therefor, a ratchet mechanism associated with said actuating member, a locking mechanism comprising a plurality of oscillatory cams for releasably holding said lifting member against involuntary descent under load, an automatic controlling mechanism having a movable part thereof constructed and arranged with reference to a fixed part thereof whereby to centrifugally retard the descent of said lifting member upon release of said locking mechanism, said parts being disposed about a fixed axis of support on the movable member, and said mechanisms associated in train by gearing designed to drive said movable part at a higher rate of speed than that of the revolute actuating member.

2. In combination, a casing, an actuating shaft therein having a ratchet mechanism including a loosely mounted gear wheel, a pinion in mesh therewith provided with a spur gear having an annular band, a plurality of locking cams carried by said casing and normally locking with said spur gear band, a shaft mounted in said casing and provided with a sleeve having a pinion meshed with said spur gear, a fixed brake band concentric with said shaft, a rotary disk carried by said sleeve and pivotally provided near its margin with a plurality of lever brake

shoes designed to flexibly engage said fixed brake band as the disk rotates, said locking cams being provided with a manually operated lever extending through said casing.

3. In a jack, the combination of a support, an actuating shaft therein having a ratchet mechanism including a loosely mounted gear wheel, a pinion in mesh with said wheel, a spur gear connected to said pinion and provided with an annular band, a plurality of locking cams arranged within said band, a spring for normally urging said cams into locking relation with said band, manual means for releasing said cams against the force of said spring, a sleeve mounted in said support and provided with a pinion meshing with said spur gear, a stationary brake band concentric with said sleeve, a disk carried by the sleeve, a plurality of brake shoes mounted on said disk and adapted to engage said band, centrifugally actuated means for forcing said brake shoes into engagement with said band, and a lifting member connected with said shaft.

4. In a lifting jack, the combination of a casing, a lifting member movable therein, a rotatable shaft for actuating said member, ratchet mechanism connected with said shaft, locking mechanism for preventing reverse rotation of said shaft, comprising a pair of locking cams mounted in said casing, an annular rotatable band surrounding said cams and operatively connected with said shaft, means for normally urging said cams into locking relation with said band, manual means for releasing said cams, and a control mechanism comprising a rotatable disk connected to and adapted to be actuated by rotation of said band, a plurality of centrifugally-actuated brake shoes carried by said disk, and a stationary drum surrounding said brake shoes and adapted to be engaged thereby.

5. In a lifting jack, the combination of a casing, a lifting member mounted therein, a shaft for actuating said member, a gear wheel surrounding said shaft, pawl and ratchet connections between said wheel and said shaft, an annular drum adapted to be rotated by said gear wheel, a plurality of cams mounted within said drum, means for normally urging said cams into locking relation with the drum, manual means for releasing said cams, a disk connected to and adapted to be rotated by said drum, a plurality of centrifugally actuated brake shoes carried by said disk, and a stationary drum surrounding said shoes and adapted to be engaged thereby for controlling the speed of rotation of said shaft.

W. HERBERT FOWKES.
